UNITED STATES PATENT OFFICE.

MARCUS PHILLIPS, OF CHICAGO, ILLINOIS.

CATAMARAN.

1,130,627.

Specification of Letters Patent.

Patented Mar. 2, 1915.

Application filed May 22, 1911. Serial No. 628,658.

To all whom it may concern:

Be it known that I, MARCUS PHILLIPS, a citizen of the United States, residing at Chicago, in the county of Cook and State of Illinois, have invented new and useful Improvements in Catamarans, of which the following is a specification, reference being had to the accompanying drawings, forming a part thereof.

10 The purpose of this invention is to provide in a catamaran or boat having two hulls, novel means of propulsion and steering, including rigging adapting the boat to be used as a sailing craft.

15 It consists of the features and elements described and shown in the drawings as indicated in the claims.

In the drawings: Figure 1 is a top plan view of the catamaran embodying this invention, the sail rigging being removed. Fig. 2 is a vertical section taken as indicated at line 2—2 on Fig. 1. Fig. 3 is a detail vertical section of the motor taken as indicated at line 3—3 on Fig. 1. Fig. 4 is a detail section taken as indicated at line 4—4 on Fig. 3. Fig. 5 is a detail of the swiveled fulcrum block for the motor lever. Fig. 6 is a sectional view of the same taken as indicated at line 6—6 on Fig. 5. Fig. 7 is a detail of the adjustable connection between the motor lever and the connecting rod. Fig. 8 is a section taken as indicated at line 8—8 on Fig. 7. Fig. 9 is an elevation of the stern of one of the hulls, being a section taken as indicated at line 9—9 on Fig. 10. Fig. 10 is a stern view of the parts illustrated in Fig. 9. Fig. 11 is a detail section taken as indicated at line 11—11 on Fig. 10.

Referring to Fig. 1, it will be seen that 40 the catamaran here illustrated is similar in a general way to that shown and described in my pending application Serial No. 514,861, filed August 27th, 1909. It consists of a pair of hulls, A, connected together by laterally 45 extending couplings, B, each formed of a piece of heavy spring rod coiled at two places, B¹, around wooden cores, C, the straight portion, B², of the rod intervening between these coils, B¹, occupies the interval 50 between the hulls, serving to space them apart, while the ends, B³, of the rod extending outwardly from the coils, B¹, engage the hulls for connecting them. As illustrated, these ends, B³, pass through the coamings, 55 A¹, of the respective hulls which are provided with bearing blocks, A², against which

the securing nuts, B⁴, are tightened. As explained in my pending application above referred to, the coils, B¹, introduce a certain flexibility in the connections, allowing each 60 hull a limited amount of movement independent of the other hull, and thus rendering the entire craft better adapted for riding any waves or rough water. The present construction differs from that of said application in that the members, B³, extend completely across each hull, throwing the strain upon it more as a whole than when they are connected to one side only of the hull; and the two connectors, B, located near each end 65 of the hulls, are placed so that the portions, B², are spaced apart by the coils, B¹, instead of lying adjacent as in the older arrangement, thus allowing somewhat easier action 70 during flexure and eliminating friction between the portions, B². In addition to these flexible couplings there is provided at each end a connector, D, composed of an angle iron having each end secured to the stem or stern posts of the hulls, as the case may be, 75 by means of a screw, E, engaging a horizontal slot, D¹, this detail of construction being fully illustrated in Figs. 10 and 11. The purpose of these angle iron cross beams, D, is not so much to connect the hulls as to 80 serve as supports for the forward deck, F, and the rearwardly extending frame boards, G; the wooden cores, C, contained in the forward coils, B¹, extend ahead to the cross beams, D, to which they are secured; but the 85 cores, C, in the stern coils, B¹, do not extend materially beyond the limits of the coils, serving merely to prevent distortion of the latter away from their proper axes. The forward deck, E, and the rearwardly extending 90 frame, G, constitute a substantially continuous unitary structure connecting the front and rear cross beams, D. These beams being pivotally connected to the hulls at bow and stern, respectively, and at the longitudinal axial lines of the hulls, it will be seen 95 that when the hulls rock about their longitudinal axes toward and from each other, the coils, B¹, and the portion of the rods of which they are made which extend across the 100 interval between the hulls will move up and down relatively to the beams, D, and that if the deck were lodged only on these rods, it would be constantly subjected to the maximum rising and falling movement resulting from the rocking of the hulls; but 105 by supporting the deck, as described, upon

the beams, D, which are in turn supported at the longitudinal axes of the hulls, the minimum rising and falling movement of the deck results from the rocking of the hulls; and in addition to this advantage, 5 there is obtained the further advantage that as the hulls rocking about their axes swing upward at their inner proximate sides, the transversely-extending portions, B², of the connectors, B, are carried upward against the under side of the deck and checked thereby, the deck tending to be bowed upward longitudinally to some extent and to operate to limit the rolling or rocking of the hulls. 10 By extending the wooden cores, C, of the forward coils forward to the forward cross beam, D, and attaching them to that cross beam, the transversely extending portions, B², of the forward connectors are kept in 15 the same plane with the forward transverse beam, D, in the rocking of the hulls; and thereby when the hulls rock upward at their proximate sides, the transversely extending portions, B², of both of the forward connectors are made to bear upwardly against the under side of the deck and share the load and duty of checking the rocking, as above described. 20 This is not important at the rear, where the deck is reduced to the mere frame boards, G, because the load upon the structure intermediate the hulls is carried chiefly at the forward portion where the deck is complete. Just forward of the middle seat in each hull there extends a connecting rod, H, of somewhat heavier material than the couplings, B, but, nevertheless sufficiently flexible to bend readily in accommodating itself to any relative movement of the hulls. Upon this cross tie, H, is mounted 25 the propeller shaft bearing and the motor, which as illustrated, is of a very simple hand power type. The casting, J, which contains a bushing, J¹, suitable to serve as a journal bearing for the propeller shaft, K, is also formed with a lug, J², and a cap, J³, therefore, 30 by which the casting is secured to the cross tie, H, in such a manner as to permit its being rocked about the tie rod in a vertical plane. The upper side of the casting, 35 J, is formed with a journal cup, J⁴, carrying a journal bushing, J⁵, secured therein by one or more set screws, J⁶. Into this cup extends the short stud axle, L¹, of the driving gear, L, of the motor; a flange, L², at the lower end of the axle is engaged by the bushing, J⁵, and the driving gear is thus prevented from coming out of its bearing. In order to obtain this arrangement, the bushing must be inserted into the cup, J⁴, with the axle, having been previously applied thereto; such application would be accomplished by splitting the bushing, as indicated at J⁷, in Fig. 4, and spreading it sufficiently to embrace the axle, L¹, after which, since it 40 would be of comparatively soft material, it

could be pressed snugly about the axle and inserted into the cup, J⁴, into which it would then be secured by the set screws, J⁶. The journal cup, J⁴, is also provided with a grease cup, J⁸, for supplying lubricant to 70 this principal bearing of the motor. Rigidly secured to the shaft, K, is the driven gear, M, meshing with the driving gear, L; and upon the extreme end of the shaft there is mounted a fly wheel, N, keyed thereto by a 75 screw, N¹, set into the end of the shaft so as to engage both the shaft and the hub of the fly wheel. The fly wheel is so cupped or hollowed out as to completely contain the driven gear, M, within the limits of its extent along the axis of the shaft. This design not only affords compactness of arrangement, but as may be noted by a consideration of the plan view of Fig. 1, it constitutes the 80 rim of the fly wheel a guard for the intermeshing gears, L and M, since with the directional relations as indicated by the arrows on said figure, it is evident that if the hand or clothing of a passenger should be engaged by the driving wheel, L, and carried 85 toward the point where it enters the hollow of the fly wheel, N, it would tend to be carried away from this point and out of danger, by the direction of rotation of the fly wheel. The fly wheel also serves as a hood 90 to protect the gear, M, from rain, and in this connection it may be noted that the entire design of the motor is such as to forestall any trouble from this source, the driving gear, L, being smooth and flat on top and 95 effectually hooding its own journal bearing. As shown, the operating lever, O, is pivoted at, O¹, nearer one end than the other, so that in the case of two operators, the one using the handle, O², has a considerably greater 100 leverage and longer swing than the one at, O³; it has been found, however, that for ordinary purposes the motor is sufficiently powerful when operated by one person only, so the handle, O³, would not often be brought 105 into service. In order to make the action somewhat easier, by not confining it to an absolute plane, the lever is pivoted in a swiveled block, P, shown in detail in Figs. 110 5 and 6, whose horizontally extending journal studs, carried in bearings, Q, permit vertical movement of the operating handle, resulting in an action somewhat similar to that experienced in rowing. The bearings, 115 Q, are shown mounted upon the ends of the frame members, Q¹, which support at their opposite ends a segment, Q², shod with a wearing plate for the lever, O. The frame members, Q¹, are bolted rigidly to the rearwardly extending frame boards, G, whose forward ends lie lapping the rearwardly extending portion of the deck, F, just over the tie rod, H. Since the lever, O, may be carried out of the plane of the driving gear, L, either by the movement of the hulls, A, rel- 120 125 130

ative to each other, or by such operation as is permitted by its swiveled pivot, O^1 , the connecting link, R , is provided with a joint at, R^1 , near its connection with the crank pin, L^3 , of the driving gear.

To permit of varying the stroke and leverage of the operating lever, O , there is provided therein a slot, O^4 , in which may be clamped at any position throughout its length the pivot pin, R^2 , through which the connecting link, R , is driven by the lever. In order, however, that such readjustment may not disturb the relation of the range of movement of the lever to the seat occupied by the operator, and thus interfere with convenience of operation, the connecting link, R , is provided with a series of holes, R^3 , to the proper one of which the pivot pin, R^2 , may be moved to correct any change of angle of the lever, O , resulting from a change of position of the pin, R^2 , in the slot, R^4 . These details are shown on an enlarged scale in Figs. 7 and 8.

Passing now to Figs. 9 and 10, it may be noted that the propeller shaft, K , carrying the propeller, S , extends obliquely downward from the motor into the water in its normal driving position, indicated in dotted lines in Fig. 9. Just forward of the propeller, the shaft is supported in this position in a stirrup, T , pivotally hung from brackets, T^1 , secured to the cross beam, D , at the stern of the craft. For removing the propeller from the water, in case shallows are encountered or some other means of propulsion is to be employed, there is provided a handle, T^2 , connected to the stirrup, T , by a link, T^3 , and extending downward through a slot, T^4 , in the plate, T^5 , which appears in Fig. 1, mounted upon the converging frame boards, G . By pulling up on this handle, T^2 , until the shaft, K , comes to the horizontal position, indicated in full lines in Fig. 9, and then swinging the handle down over the post, T^6 , and fastening it down by means of the pivoted button, T^7 , the shaft may be securely locked in such elevated position with the propeller, S , clear of the water. This raising of the propeller shaft results in no bending or distortion of the shaft, since the journal casting, J , is pivotally connected to the tie rod, H , at, J^2 ; neither is the relation of the gears, L and M , disturbed, inasmuch as the entire motor, exclusive of the lever, O , and its connecting rod, R , is carried by the journal casting, J , and the shaft therein, so that it swings as a whole about the tie rod, H , when the propeller is raised above the water line. The change of angle of the crank pin, L^3 , relative to the connecting rod, R , is permitted by the pivotal connection in the connecting rod at, R^1 .

Figs. 9 and 10 in connection with Fig. 1, also illustrate the steering devices for this

catamaran, which comprise a pair of rudders, U , pivotally mounted, one at the stern of each hull, A , and connected for simultaneous operation by rods, U^1 , extending from bell crank arms, U^2 , on the rudders, respectively, to the opposite ends of a tiller lever, U^3 , pivoted at its mid-point on a cross member, U^4 , carried by the frame boards, G .

I claim:—

1. In a catamaran, in combination with the two hulls, members laterally connecting said hulls, each comprising a rod formed with spring coils at two places in its length, such connectors being employed in pairs positioned with the corresponding middle portions between the coils separated longitudinally of the hulls and occupying the interval between them, the coils lying within the fore and aft interval between said middle portions, and the extending ends of the coils engaging the respective hulls in pairs adjacent to each other.

2. In a catamaran, in combination with the two hulls, members laterally connecting said hulls, each comprising a rod formed with spring coils at two places in its length, the portion of the rod between said coils occupying the interval between the hulls and the extending end of each coil projecting transversely of one of the hulls and engaging said hull at both sides thereof.

3. In a catamaran, in combination with the two hulls, members laterally connecting said hulls, each comprising a rod formed with spring coils at two places in its length, such connectors being employed in pairs, each pair being arranged with its coils axially aligned in pairs, and a separate cylindrical core axially located in each pair of coils thus aligned.

4. In a catamaran, in combination with two hulls, flexible connectors joining said hulls and laterally spacing them apart; beams which connect the two hulls at their forward and rear ends, said beams being pivoted to the hulls substantially at the ends of their longitudinal axes, whereby each hull is adapted to rock about its said axis, and a deck positioned in the interval between the hulls and supported upon said transverse end beams.

5. In a catamaran, in combination with two hulls, flexible connectors joining said hulls and laterally spacing them apart; beams which connect the two hulls at their forward and rear ends, said beams being pivoted to the hulls substantially at the ends of their longitudinal axes, whereby each hull is adapted to rock about its said axis, and a deck positioned in the interval between the hulls and supported upon said transverse end beams, said deck intermediate its ends being lodged upon said flexible connectors.

6. In a catamaran, in combination with

- two hulls, flexible connectors joining said hulls and laterally spacing them apart; rigid beams pivotally connecting the hulls at their front and rear ends substantially at their longitudinal axes; connectors each comprising a rod formed with spring coils, one adjacent to each hull; core rods extending axially through the coils adjacent to the hulls respectively, and thence forward to the forward transverse beam and joined thereto, and a deck extending in the interval between the hulls mounted with its forward end upon the forward transverse bar and lodged upon the forward connectors.
7. In a catamaran, in combination with the two hulls, members laterally connecting said hulls, each comprising a rod formed with spring coils at two places in its length, such connectors being employed with the middle portions of the rods which connect the coils occupying the interval between the hulls, and with the coils of each connector axially alined with the corresponding coils of the other connectors, the connectors being arranged at intervals fore and aft of the hulls, a deck partially supported by such connectors in the interval between the hulls, an additional support for said deck comprising a comparatively rigid beam, and horizontal pivot pins projecting from the ends of the respective hulls engaging horizontal slots in the beam.
8. In a catamaran, in combination with the two hulls, members laterally connecting
- said hulls, each comprising a rod formed with spring coils at two places in its length, the portion of the rod between said coils occupying the interval between the hulls, a deck partially supported upon said middle portion of the connector, a cross beam pivotally connecting the corresponding ends of the hulls, and also supporting the deck, cylindrical cores axially located in each coil of one of the connectors extending longitudinally of the hulls to the cross beam and connected therewith.
9. In a catamaran, in combination with the two hulls, means laterally connecting said hulls, a motor supported thereby in the interval between the hulls, a propeller shaft extending aft from the motor, a support for the rear end of the propeller shaft comprising a U-shaped hanger, the propeller shaft being lodged in the bend of said hanger and the ends thereof being pivotally hung from a member which connects the two hulls, and an operating connection adapted for swinging said hanger and the shaft which it carries, up above the water line.
- In testimony whereof, I have hereunto set my hand at Chicago, Illinois, this 19th day of May, 1911.

MARCUS PHILLIPS.
